UNITED STATES PATENT OFFICE.

GEORG WILHELM VON SIEMENS AND AUGUST WILHELM HUGO ROTTI, OF BERLIN, GERMANY, ASSIGNORS TO THE SIEMENS & HALSKE ELECTRIC COMPANY OF AMERICA, OF CHICAGO, ILLINOIS.

MEANS FOR COOLING DYNAMO-ELECTRIC MACHINES.

SPECIFICATION forming part of Letters Patent No. 616,979, dated January 3, 1899.

Application filed October 22, 1898. Serial No. 694,280. (No model.)

To all whom it may concern:

Be it known that we, GEORG WILHELM VON SIEMENS and AUGUST WILHELM HUGO ROTTI, subjects of the Emperor of Germany, residing at Berlin, Germany, have invented a certain new and useful Improvement in Means for Cooling Dynamo-Electric Machines, (Case No. 173,) of which the following is a full, clear, concise, and exact description.

- 10 Our invention relates to improvements in means for cooling dynamo-electric machines, and has for its object the association of parts in such a machine whereby air is effectively directed against the heated surfaces of the 15 dynamo when in operation for the purpose of reducing the temperature thereof. We have made careful investigations along this line and find that in many types of dynamo-electric machines wherein ventilation has previously 20 been employed comparatively poor results have been attained even when securing the movement of large quantities of air through the ventilating-openings of the machines. Experiment has demonstrated that 25 greater efficiency is secured by the movement of a comparatively small quantity of air past the heated parts, if properly directed against the same, than is attained by ordinary methods when very large quantities of air rush 30 through the openings in the dynamo-electric machine. It is highly desirable that each of two requirements be met in order to secure the best results. First, the air must be conducted directly against the heated surfaces 35 of the machine which are to be cooled, and arrangements preferably are provided whereby a comparatively large surface of metal may be exposed to the currents of air, and, secondly, the air-currents should be forced 40 with great rapidity past the surfaces to be cooled, and by imparting to currents a whirling motion a very much greater amount of heat is taken up thereby, in view of the limited surfaces of the parts exposed, than is 45 otherwise attainable. Our invention is directed toward the end of providing a construction adapted to secure these results, wherein comparatively narrow air-channels are provided which limit the flow of air to a rela-

tively small column, combined with means for 50 securing a high velocity of the air moved past as great an area as possible of heat-radiating surface in the field-magnets and armature of a dynamo. We may briefly describe the dynamo-electric machine, in connection with 55 which we will set forth our invention more fully as containing a suction-fan mounted upon the shaft of the armature and rotating within a partially-closed chamber, which is adapted to draw air from the opposite side of 60 said machine through comparatively narrow air-passages, which are constructed in whole or in part to secure a rotary movement of the air. Corrugated sheet metal is employed to increase the radiating-surface, if desired, and 65 a diaphragm provided except at the central opening prevents the dispersion of air-currents flowing through the machine.

The construction will be more readily comprehended by reference to the accompanying drawings, wherein—

Figure 1 is a side view of said dynamo-electric machine, partially broken away and in section. Fig. 2 is a vertical sectional view on line 2 2 of Fig. 1. Fig. 3 is an oblique sectional view on line 3 3 of Fig. 1.

The same letter of reference is used to designate like parts in each of the figures of the drawings.

The machine to which we have shown our 80 invention applied is a four-pole dynamo-electric machine having its right side developed to form a suction air-fan which is adapted to move the air rapidly through the dynamo from side to side in air-passages especially 85 provided therefor.

The circular frame *a* carries the four poles *b* of the dynamo, the armature *c* being rotatably mounted upon the shaft *c'*, rotating within laterally-extending arms *a'* of the frame. Upon the right side of the machine (see Fig. 2) are mounted the blades *d'* of the suction fan *d*, which rotate in a partially-closed chamber *d'*. This chamber is formed by the outer diaphragm *e*, which is secured to the frame of the machine, and the inner diaphragm *f*, wherein is provided a circular opening *f'* approximately the size of the armature.

Upon the right-hand side of the frame are provided the peripheral openings *e'*, which serve as discharge-outlets for the air. The field-windings are provided with inclosing sheet-metal casings *g*, which extend from side to side upon the adjacent faces of the same and conform to the armature-opening of the machine. Between said field-windings and the casings are provided corrugated sheet-metal strips *g'*, which engage said windings and increase the heat-radiating surface thereof. The commutator of the machine and the armature are provided with lateral openings *h k*, through which the air readily passes from side to side. In the openings *k*, provided through the laminated core of the armature, are disposed the spiral metal strips *k'*, which impart to the air flowing through said openings a rotary motion and direct the same intimately upon the exposed surfaces of the armature-core.

In Figs. 2 and 3 we have illustrated by means of arrows the flow of air-currents, which are forced through the machine with great rapidity from side to side when the dynamo is in operation. It will be seen that all parts of the machine that are liable to become heated have directed against them in the most efficient manner quantities of air proportionate to the velocity with which the armature rotates, and the field-magnets and the armature will accordingly be maintained comparatively cool by small quantities of air, which follow the conformation of these parts. The radiating-surfaces of any of the parts may be greatly increased, as indicated, by the use of thin sheets of corrugated metal disposed in contact with said parts, and the rotary or whirling movement which it is desirable to impart to the air is readily secured by the use of the metallic spirals *k'*. By employing the casings *g*, which conform to the exteriors of the fields and armature, narrow air-passages are provided which force the air into intimate contact with the respective parts, and, in connection with the diaphragm *f*, the movement of inefficient quantities of air between the widely-separated parts is prevented. The armature, which is particularly liable to heating, is provided with means for ventilating the same, since its core-openings constitute a central passage-way for the air drawn through the machine by means of the fan, and its periphery is likewise in constant engagement with rapidly-flowing currents of air, which take up the radiated heat.

It is sometimes found in the use of our invention, that the air of the dynamo-room is not sufficiently cool to secure the best results, and we have frequently found it desirable to take air for ventilating purposes from the exterior or a cooling-chamber in order to secure the necessary radiation of the heat from the dynamo. It is obvious that the air may either be forced or drawn through the machine, and the fan *d* may, if desired, be constructed to drive the air through the machine

in the manner described instead of operating upon the principle of suction, as is set forth above. Highly-satisfactory results may be obtained by connecting the ventilating-chamber *d* with the chimney of the power-station, and in some instances sufficient draft may thus be obtained to secure the entire flow of air necessary for the purposes of cooling the dynamos.

It is obvious that numerous changes in the construction herein shown and described may be made without departing from the spirit of our invention, and we do not desire to be understood as limiting the same to the precise form of apparatus or application of the principles herein disclosed.

We claim, therefore, and desire to secure by Letters Patent—

1. In a dynamo-electric machine, the combination with casings *g* conforming approximately to the profile of the field-magnet windings and armature but separated therefrom, whereby narrow air-passages are provided in said machine, of means for effecting the rapid flow of air-currents through said passages, substantially as described.

2. In a dynamo-electric machine, the combination with the casings *g* conforming approximately to the exterior surfaces of the inclosed parts but separated therefrom, whereby lateral air-passages are provided in said machine, of means for effecting the rapid flow of air-currents laterally through said air-passages, whereby said surfaces of the machine are cooled, substantially as described.

3. In a dynamo-electric machine, the combination with the casings *g* conforming approximately to the exterior surfaces of the inclosed parts but separated therefrom, whereby lateral air-passages are provided in said machine, of a fan associated with said machine adapted to effect the rapid flow of air-currents laterally through said air-passages, whereby the said surfaces of the machine are cooled, substantially as described.

4. In a dynamo-electric machine, the combination with the windings thereof, of corrugated sheet metal disposed in contact with said windings, whereby the radiating-surface thereof is augmented, substantially as described.

5. The combination, in a dynamo-electric machine, with the ventilating-passages thereof, of corrugated sheet metal disposed in said ventilating-passages in contact with the surfaces of the machine, whereby the radiating-surfaces of the parts are augmented, substantially as described.

6. In a dynamo-electric machine, the combination with the ventilating-passages thereof, of spirals *k'* disposed therein and adapted to impart to the currents of air flowing through said passages a rotary movement, substantially as described.

7. The combination, in a dynamo-electric machine, with air-passages *h* provided in the armature thereof, of means associated there-

with for securing the rotary movement of the air flowing in said passages, substantially as described.

8. The combination with a dynamo-electric machine, of casings *g* conforming generally to the exteriors of the part or parts likely to be heated, air-passages provided between the said part or parts and the casings *g*, and means for securing the rapid flow of air through said passages, substantially as described.

9. In a dynamo-electric machine, the combination with the parts thereof likely to be heated, of corrugated sheets *g'* disposed in engagement with said parts and adapted to increase the heat-radiating surfaces thereof, substantially as described.

10. The combination with a dynamo-electric machine, of a fan *d* adapted to secure the flow of air through the ventilating-passages thereof, and a diaphragm *f* adapted to close the lateral openings of said dynamo-electric machine but permitting the flow of air through the ventilating-passages of said machine, substantially as described.

11. The combination in a dynamo-electric machine, with a fan *d* adapted to secure the

flow of air through the ventilating-passages of said machine, of the diaphragm *f*, the casings *g* conforming approximately to the exteriors of the field-windings and armature of said machine and providing ventilating-passages around the same, and ventilating-openings *k* disposed in the armature-core, substantially as described.

12. In a dynamo-electric machine, the combination with the casings *g* conforming approximately to the exteriors of the field-windings and armature, of corrugated sheets *g'* disposed throughout a portion of the ventilating-passages provided thereabout, ventilating-openings *k* provided in the core of the armature, spirals *k'* disposed therein, diaphragm *f*, and means for effecting the flow of air through the ventilating-openings in the dynamo, substantially as described.

In witness whereof we hereunto subscribe our names this 14th day of September, A. D. 1898.

GEORG WILHELM VON SIEMENS.
AUGUST WILHELM HUGO ROTTI.
